By Thorpe Gerard Atty.

UNITED STATES PATENT OFFICE.

JEPHTHA G. HOLLINGSWORTH, OF KANSAS CITY, MISSOURI.

ANATOMICALLY-ARTICULATED ARTIFICIAL TEETH AND METHOD OF PRODUCING
SAME.

Application filed January 12, 1923. Serial No. 612,231.

To all whom it may concern:

Be it known that I, JEPHTHA G. HOLLINGSWORTH, a citizen of the United States, and resident of Kansas City, county of Jackson, 5 State of Missouri, have invented a certain new and useful Improvement in Anatomically-Articulated Artificial Teeth and Methods of Producing Same, of which the following is a complete specification.

10 This invention relates to prosthetic dentistry, and the objects are to produce as a factory unit, an anatomically articulated set of upper and lower artificial teeth as a new article of manufacture, and to evolve a 15 method or process of producing such article.

At the present time sets of artificial teeth are marketed under identifying symbols or names, but as far as I am aware, it has never heretofore been proposed to place upper and 20 lower sets of teeth secured as a unit, in anatomically articulated relation, in the hands of the jobber and dentist as a factory product, and thus enable the dentist to render efficient, rapid and most satisfactory service 25 to a patient, without the delay and expense incident to recourse to a prosthodontist or to the old slow method of establishing proper articulation by individual adjustment of the teeth.

30 With the object mentioned in view, the invention consists in certain novel and useful features of construction and combinations of parts as hereinafter described and claimed, and in order that it may be fully understood, 35 reference is to be had to the accompanying drawings, in which:

Figure 1 is a perspective view of a master pattern of a full set of upper and lower artificial teeth properly articulated;

40 Figure 2 is a horizontal section of the same in conjunction with a holder cast or molded upon such teeth, and adapted to be used like a printer's "stick" for setting up corresponding teeth in properly articulated relation;

45 Figure 3 is a vertical section taken through the "holder" or "stick" on the line III-III of Figure 2 and showing teeth waxed in the "holder" or "stick" at one side 50 of the median line thereof;

Figure 4 is a side elevation of a complete set of upper and lower teeth as a new article of manufacture, the same being produced in

the "holder" or "stick" and then removed therefrom;

55 Figure 5 is a horizontal section on the line V-V of Figure 4;

Figure 6 is an enlarged vertical section taken on the line VI-VI of Figure 5; and

60 Figure 7 is a blank to be folded to serve as a reinforce plate or stiffener of the product constituting a new article of manufacture.

Referring first to the article or product to be carried in stock by dental depots or jobbers for retail to dentists, 1 and 2 respectively indicate upper and lower sets of teeth arranged in proper anatomical and articulated relation, and 3 indicates relatively hard wax or the like, securing the teeth in such relation. Fitting within the arch formed by and between the teeth and corresponding in contour substantially to such arch, is a reinforce plate or stiffener 4, the wax 3 or the like, being interlocked with said plate in any suitable manner, preferably by providing the plate with marginal flanges 5, embedded in the wax as shown clearly by Figure 6. The plate is preferably of doubled or folded type so that the flanges project both upwardly and downwardly, and is preferably produced from a substantially elliptical blank flanged at its outer edge and then folded on the dotted line a, (see Figure 7).

65 As the use by the dentist contemplates the ready separation of the upper and lower sets of teeth preparatory to vulcanizing or otherwise securing them to the customary final mouth plates, not shown, it is desirable 70 in producing the product, to prevent wax 3 or the like, from coming in contact with the sets of teeth at or close to the biting edges thereof, and to accomplish this, compressible wax 6 or the like is applied to the flanged edge of the reinforce plate, to hold a strip of tinfoil 7 or other suitable material pressed against the two sets of teeth in bridging relation to their meeting or cutting edges, the 75 plate and strip of tinfoil or the like, being fitted in operative position with relation to the teeth, before the wax 3 is applied,—at least before that portion of such wax is applied to bind or secure the plate and hence the tinfoil in place, as that part of the wax 80 3, applied on and between the upper parts

of the upper teeth and the lower parts of the lower teeth, may be applied to hold the teeth against disarrangement while the plate and tinfoil is being fitted in place. The remainder of the wax 3, i. e., the major portion thereof is then applied to adhere to the teeth or to the first portion of such wax applied, and to interlock with the plate to cooperate therewith in retaining the tinfoil in place. The wax 3 will be of such character that it will not soften under ordinary natural heat of summer, and hence will guard against slippage or disarrangement of the teeth under ordinary conditions, or handling, but will readily yield to paring by a knife and can be instantly cut with a heated knife or tool.

As to the method of accurately disposing the sets of teeth in anatomical and articulated relation, and then securing them in such relation so that they can be shipped as a factory product of the character above described, reference is to be had to what I term the "holder" or "stick." This is in the form of two cast or molded segments 8-8, fitted together endwise to conjointly form an arch, provided internally with cavities 9 for the reception of specified upper and lower sets of teeth, which teeth are fitted in their respective cavities by hand, small pieces of dental wax eventually forming part of wax 3, being applied between adjacent upper teeth and adjacent lower teeth to insure the retention thereof until both full sets have been secured, after which the new article is completed as hereinbefore explained. The "holder" or "stick" is then detached, and to accomplish this easily and without applying force tending to distort the product or article, the two sections of the "holder" or "stick" are mounted on the free end of separable arms 10 of a metal handle, the two arms being normally clamped together by a slideable keeper 11. The handle has a cross head 12 of sufficient area when placed on a bench, to support the "holder" or "stick" in inverted position to facilitate the assembly and retention of the front teeth and incisors in the proper cavities 9. For conveniently positioning the "holder" or "stick" for the placement of the molars in their respective cavities, the sides of the segments are flat so that such sides and the corresponding ends of the cross head may rest upon the upper side of the bench. In Figure 2, the dotted lines X are assumed to be the top of the bench accordingly as the flat side of one segment and the corresponding end of the cross head are engaging the bench, to support the corresponding molars in place until waxed in place. The "holder" or "stick" is then reversed to facilitate the placement of the other molars, these operations of course being followed by the completion of the article or product as it ap-

pears in Figures 4 to 6, inclusive. The keeper is then slid toward the cross head to permit the free ends of the handle to move outward and withdraw the segments from engagement with the teeth.

The "holder" or "stick" is for use in a factory, and enables one entirely ignorant of the art of dental articulation, to anatomically articulate sets of teeth as perfectly and far more economically and quickly than it is possible for a prosthodontist to accomplish the same purpose in the conventional manner.

The segmental "holder" or "stick" is scientifically perfect and is produced by molding or casting it from an anatomically perfect master pattern 13 made by a skilled prosthodontist or dentist, it being understood that there will be a master pattern for each of the many differently identified sets of teeth necessary to meet the requirements of practice.

The construction of the commercial product, the method followed in producing it, the construction of the "holder" or "stick" and its use, having been described, reference is now made to the method by which the article or product is handled by the dentist, who, after applying soft wax 14 or the like, to trial plates 15 and 16, fits the latter, produced in the usual manner, into the jaws of the patient or a suitable articulator.

The article or product is then inserted in the patient's mouth or the articulator as the case may be, and adjusted as a unit to a position which the dentist deems most satisfactory from the standpoint of utility and appearance. The jaws are then closed so that the soft wax shall unite the article to the trial plates, the wax being soft enough to provide for a substantial embedment therein of the teeth and of adhesive character to insure a firm union of the teeth with the trial plates.

The jaws are then opened to permit of the removal of the trial plates and the article as a unit. Any suitable means, such as a heated knife (not shown) is then employed to cut through the wax 3 on the dotted lines y and z. This result accomplished, the reinforce plate and the tinfoil (or the central part of the latter) are removed, leaving the upper and lower sets of teeth and their respective trial plates in disconnected and separable condition.

The teeth thus affixed to their respective trial plates are then "waxed up" and "flasked" by the method now customary, and when finally secured on the permanent mouth plates, the teeth in the mouth of the patient, articulate upon closure of the jaws identically as the corresponding teeth in the master pattern and in the "holder" or "stick" articulate because the teeth from the time they were placed in the "stick" have

never been individually moved or adjusted.

From the above description it will thus be apparent that I have produced a device embodying the features or advantage enumerated as desirable in the statement of the object of the invention, and while I have illustrated and described the preferred form or embodiment of the invention, it will be apparent that it is susceptible of modification in minor particulars without departing from the principle of construction or mode of operation involved.

I claim:

1. As a new article of manufacture, a set of upper and lower teeth, means affixed to the teeth and holding both sets as a unit, in anatomical and occluded relation, and means bridging the biting edges of both sets of teeth and interposed between the teeth and the first-named means.

2. As a new article of manufacture, a set of upper and lower teeth, means affixed to both sets of teeth and holding them as a unit, in anatomical and occluded relation, and a plate within the arch of the teeth and interlocked with the said means as a stiffener therefor.

3. As a new article of manufacture, a set of upper and lower teeth, means affixed to both sets of teeth and holding them as a unit in anatomical and occluded relation, means bridging the biting edges of both sets of teeth and interposed between them and the first-named means, and a plate within the arch of the teeth and interlocked with said first-named means as a stiffener therefor.

4. As a new article of manufacture a set of upper and lower teeth, a material susceptible of being melted, affixed to both sets of teeth to retain them as a unit, in anatomical and occluded relation, and means bridging the biting edges of both sets of teeth and interposed between the teeth and the first-named means.

5. As a new article of manufacture a set of upper and lower teeth, a material susceptible of being melted, affixed to both sets of teeth to retain them as a unit, in anatomical and occluded relation, and a plate within the arch of the teeth and interlocked with the said means as a stiffener therefor.

6. As a new article of manufacture a set of upper and lower teeth, a material susceptible of being melted, affixed to both sets of teeth to retain them as a unit, in anatomical and occluded relation, a stiffener plate within the arch of the teeth and interlocked with said material, and a flexible strip secured to the said material and plate and interposed between them and the teeth at the biting edges of the latter.

7. The method of producing a set of upper and lower teeth held as a unit in anatomical and occluded relation, the same consisting in forming from a master pattern, a segmental "holder" or "stick" having upper and lower tooth cavities in its inner side, placing corresponding teeth in said cavities, waxing both sets of teeth together, and in withdrawing the "stick" from the teeth.

8. The method of producing a set of upper and lower teeth held as a unit in anatomical and occluded relation, the same consisting in forming from a master pattern, a segmental "holder" or "stick" having upper and lower tooth cavities in its inner side, placing corresponding teeth in said cavities, waxing both sets of teeth together, interlocking a stiffener plate with the wax, and in interposing a flexible strip between the wax and plate and the teeth at the biting edges thereof.

9. In a method of producing as a unit sets of upper and lower teeth in anatomical and occluded relation, a "holder" or "stick" for both sets of teeth, comprising two separable segments abutted together at the median line of the sets of teeth, and provided at their inner sides with communicating upper and lower teeth cavities for the reception of the respective teeth at the buccal faces thereof.

10. As a new article of manufacture, a pair of arcuate plates arranged and secured flatwise together, and a set of upper and lower teeth having their biting edges in articulated and occluded relation, both the upper and lower teeth being respectively secured as a unit to one of said plates.

In witness whereof I hereunto affix my signature.

JEPTHA G. HOLLINGSWORTH.
